FIRE HYDRANT

Donald E. Watkins, Cleveland, Ohio, assignor to Mueller
Co., Decatur, Ill., a corporation of Illinois

Filed Aug. 26, 1960, Ser. No. 61,901

Term of patent 14 years

(Cl. D91—3)

FIG. 1.

FIG. 2.

FIGURE 1 of the drawing gives a perspective view of one side of a fire hydrant embodying my design. The other side of the hydrant is substantially plain.

FIGURE 2 of the drawing is a top view of the hydrant shown in FIGURE 1.

This application is a continuation-in-part of my prior application Serial No. 57,550, filed September 14, 1959, and now abandoned.

I claim:
The ornamental design for a fire hydrant, as shown.
